UNITED STATES PATENT OFFICE

ALEXANDER P. FOX, OF UNIVERSITY CITY, MISSOURI, ASSIGNOR TO LINCOLN
ENGINEERING COMPANY, OF ST. LOUIS, MISSOURI, A CORPORATION OF MISSOURI

DESIGN FOR A LUBRICATING APPARATUS

Application filed January 14, 1933. Serial No. 46,833. Term of patent 14 years.

To all whom it may concern:

Be it known that I, ALEXANDER P. Fox, a citizen of the United States and a resident of University City, St. Louis County, Missouri, have invented a new, original, and ornamental Design for a Lubricating Apparatus, of which the following is a specification, reference being had to the accompanying drawing, forming part thereof, in which

Fig. 1 is a top plan view;

Fig. 2 is a side elevation; and,

Fig. 3 is a front elevation taken from the right of Fig. 2.

I claim:

The ornamental design for a lubricating apparatus, substantially as shown.

ALEXANDER P. FOX.
